UNITED STATES PATENT OFFICE.

FRANK WASHINGTON DÉ BLIEUX, OF CHICAGO, ILLINOIS.

SAFETY-PURSE.

1,189,924.

Specification of Letters Patent. Patented July 4, 1916.

Application filed January 22, 1916. Serial No. 73,551.

To all whom it may concern:

Be it known that I, F. W. DÉ BLIEUX, a citizen of the United States, residing at Chicago, in the county of Cook and State of Illinois, have invented certain new and useful Improvements in Safety-Purses, of which the following is a specification.

This invention relates to improvements in safety purses and more particularly to personal wear treasure purses.

The object of the invention is to provide a purse of this class adapted to be movably secured to the leg of the user, about the stocking, above or below the knee as may be desired. The purse is instantly movable, with relation to its supporting element, about the leg so that access thereto may be had easily while at the same time the contents of the purse are normally secured in safety. Means for effectually locking the mouth of the purse in closed position are also provided.

With the foregoing and other objects in view the invention consists in the combination and arrangement of parts to be herein-after fully described in the following specification, pointed out in the appended claims and illustrated in the accompanying drawing which forms a part of said specification and in which—

Figure 1 is a front view of my purse. Fig. 2 is a side view of the same. Fig. 3 is a side view, partly in section, with the purse in open position. Fig. 4 is a view of the purse in use upon the leg of a person.

Like reference characters denote corresponding parts throughout the several views.

The reference numeral 1 denotes an elastic band which serves as a supporting element to encircle the leg of the wearer and carry the purse, said band slidably engaging a loop 2 in a strap 3 which is attached to the purse 4. One end of the strap 3 is secured to the face of the purse, and is provided with a metal clasp 5, and passed about the same and extends longitudinally of the back of the purse and terminates in a free end 6 perforated at 7 for engagement with the said clasp 5 and perforated at 8 to permit passage therethrough of the purse clasps 9.

With the free end of the strap 3 engaged by the clasp 5 and the clasps 9 the purse is locked against accidental opening and the consequent loss of all or part of its contents obviated.

The elastic band 1 is adjustable and may be adjusted to fit the leg of the wearer, the purse is adjustable with relation to the band 1 and so may be instantly moved from one side of the leg to the other when desired. In Fig. 1 the purse is shown closed. To open the purse the clasp 5 is moved outwardly to permit the release of the free end of the strap 3 which is raised into the position shown in Fig. 3 or until it has passed out of engagement with the clasps 9; the purse may now be opened in the usual manner.

What is claimed is:—

1. A safety purse comprising an elastic supporting element, a strap permanently secured at one end to the purse and passing about the greater portion of the same and terminating in a free end having perforations therein, one of said perforations being adapted to receive the purse clasps, and a clasp carried by the secured end of said strap for engagement with a perforated portion of the free end thereof.

2. The combination with a purse provided with fastening clasps, of a strap fastened thereto so as to form a loop portion and having one of its ends perforated and free from said purse, one perforated portion of the free end of said strap being adapted to cooperate with the purse clasps when in closed relation, a clasp carried by the opposite end of said strap for engagement with another perforated portion of the free end of said strap, and an adjustable supporting element slidably engaging the looped portion of said strap.

In testimony that I claim the foregoing as my own I have hereto affixed my signature in the presence of two subscribing witnesses.

FRANK WASHINGTON DÉ BLIEUX.
